UNITED STATES PATENT OFFICE

BIRGER ENGSTROM, OF PITTSBURGH, PENNSYLVANIA, ASSIGNOR TO FORSTER MANUFACTURING COMPANY, OF PITTSBURGH, PENNSYLVANIA, A CORPORATION OF PENNSYLVANIA

TOY CANNON

Application filed February 23, 1929. Serial No. 342,040.

This invention relates to toy cannons and more particularly to toy cannons of the type used in firing gaseous explosive charges such, for example, as carbide cannons.

5 An object of this invention is to provide a cannon of the type set forth having an improved construction and mode of operation.

A further object is to provide a cannon of the type set forth of such construction and 10 arrangement as to permit of repeated and continued firing thereof.

A still further object is to provide a toy repeating cannon of simple, rugged construction which will be easy to operate and cheap 15 to manufacture and assemble.

These and other objects which will be apparent to those skilled in this particular art are attained by means of the invention illustrated in the accompanying drawings in

20 which Figure 1 is a perspective view of a cannon constructed in accordance with one embodiment of this invention. Fig. 2 is a rear view in elevation thereof. Fig. 3 is a transverse sectional view on the line 3—3 of Fig. 5, 25 certain parts being broken away. Fig. 4 is a perspective view of the rear end of the cannon and its surrounding sleeve and Fig. 5 is a longitudinal sectional view through the cannon.

30 The particular embodiment of this invention which has been chosen for the purposes of illustration includes a cannon provided with a plurality of firing chambers constructed and arranged in such a manner as to cause 35 the explosion occurring in one of the firing chambers to aid the performance of other necessary operations in the other chambers.

As illustrated, the cannon is mounted upon a base 10 provided with a suitable water receptacle 11. A barrel supporting sleeve 12 has hangers 13 by which it is mounted upon the foundation and a number of perforations 14 for the admission of scavenging or cleaning air to the firing chamber are suitably 45 formed therein. The sleeve is also provided with a touch hole 15, and a charging opening 16 is located in the bottom thereof directly over the water trough 11 with which it is connected by a shut pipe or conduit 17, or 50 the like. At the rear end of the sleeve a hole

18 is formed, see Figs. 3 and 5, for the delivery of carbide or other material which coacts with the water or other liquid to generate a gas which will explode in the presence of oxygen, or when mixed with air.

55 Firing chambers 19, which are three in number, are formed within a breech cylinder 20 by suitable partitions 21 and the breech end of the firing chambers is closed by a partition 22, broken away in Fig. 3, but fully 60 illustrated in Figs. 4 and 5. An opening 23 is formed in the wall of the breech cylinder at each firing chamber and these openings cooperate successively with the firing opening 15, the air scavenging opening 14, and 65 the charging opening 16 in the operation of the cannon.

A barrel 24 is divided by partitions 25 into three chambers which constitute extensions of the separate firing chambers and 70 the barrel and barrel chambers are secured to and rotatable with the breech cylinder 23. A suitable cover or barrel sleeve 26 is mounted upon the breech sleeve 12 and extends beyond the end of the barrel 24 so as to 75 provide a chamber 27 communicating with each of the firing chambers and through which the discharge from each firing chamber passes.

80 The partition 22 in the breech cylinder, being spaced inwardly from the rear end thereof, forms a chamber or magazine 28 adapted to receive a supply of carbide or other similar material. A breech closure or magazine cover 29 seats over the rear end of the breech sleeve 12 and forms the outer wall of the magazine 28. The wall of the breech cylinder 23 forming the magazine is provided with three openings 30, one associated 85 and located in alignment with each of the three firing chambers. The breech cylinder and barrel 25 is rotated by a hand wheel 31 connected to a gear 32 secured to a suitable gear shaft 33 rigidly secured to the breech block in any suitable manner as by mounting 90 it in the magazine wall 22. The hand wheel 31 is supported on the magazine cover 29.

95 The magazine cover 29 is provided with a charging opening for carbide through which the carbide can be delivered to the magazine 100

and this opening may normally be covered by a slidably mounted closure 34. A guard plate 35, see Figs. 3 and 5, is located in the magazine over the charging opening 18 leading to the 5 water container, and the extension of the breech block 23 forming the magazine wall having the perforations 30 rotates between the opening 18 and the guard flange 35.

In operation, assuming the magazine 28 10 to contain a quantity of carbide, the hand wheel 31 is rotated causing the breech block 23 and barrel 25 to rotate. The carbide will naturally collect within each of the openings 30 as it moves downwardly toward the charging opening 18. As the opening 30 passes a charging opening 18, this quantity of carbide is delivered therethrough to the water container 11 and the guard flange 35 prevents a surplus quantity of carbide passing 15 into the container. The acetylene generated passes upwardly through the conduit 17 and through the associated breech block opening 23 into the associated firing chamber 19. Continued rotation of the breech moves the firing 20 chamber which has received a charge of acetylene around to a position where the associated opening 23 is opposite the touch hole 15. It will be apparent that an explosion will result 25 from the operation of a suitable sparking device 36 such as that indicated in Fig. 3 opposite the touch hole 15. At the same time another charge of carbide has been deposited in the water container and additional acetylene has been delivered to the next succeeding 30 firing chamber 19. After firing the first chamber 19, further rotation of the breech moves the chamber in which the explosion has taken place around to a position where its associated breech opening 23 is opposite 35 the air inlet 14 and the next succeeding firing chamber with its explosive charge has moved around to a point where its associated opening 23 is opposite the touch hole 15, while the intermediate firing chamber is at the bottom 40 of the breech in direct communication with the conduit 17. When the explosive charge in the proper firing chamber is ignited, the explosion passes out through the associated portion of the barrel 25 and through 45 the chamber 27 in the sleeve 26 which is common to each of the firing chambers and in communication with each. The passage of the charge or explosion through this common chamber 27 results in a suction upon the other 50 two firing chambers so that scavenging air is drawn through the air inlet 14 into the connected firing chamber and fresh oxygen is thus supplied thereto, while at the same time the suction upon the firing chamber 19 at 55 the bottom of the breech causes the acetylene in the conduit 17 to be sucked upwardly into such chamber. It will be apparent that this 60 operation can be continued indefinitely and that the firing of the cannon can take place 65 at extremely rapid intervals. It will also be

apparent that the chamber 27, common to each of the firing chambers, may be formed in the barrel itself, instead of in a separate sleeve. As a matter of fact, in actual practice, I have found that the chamber 27 may be 70 materially reduced in size, or may be eliminated entirely, without destroying or noticeably affecting the operation of the gun. The fact that the barrels communicating with the separate firing chambers all terminate in a 75 common plane produces a construction in which the discharge passing from one barrel causes an entraining flow of air through the other two barrels as above described.

Although I have described in detail one 80 specific embodiment of this invention, it will be apparent that various changes, additions, omissions and substitutions can be made 85 therein without departing from the spirit of this invention or the scope of the appended claims.

What I claim as new and desire to secure by Letters Patent is:

1. In a carbide cannon, a plurality of firing 90 chambers, a gas generating chamber and means for successively connecting each of said firing chambers with said gas generating chamber.

2. In a carbide cannon, a plurality of firing 95 chambers, and means for successively delivering a charge to each of said chambers.

3. In a carbide cannon, a plurality of firing 100 chambers, a chamber common to the muzzle end of each of said firing chambers, and through which each firing chamber discharges and means for opening one firing chamber to the atmosphere at the time of the explosion in another firing chamber.

4. In a carbide cannon, a plurality of firing 105 chambers, a chamber common to the muzzle end of each of said firing chambers and through which each firing chamber discharges, a charge generating chamber and means for establishing communication between one firing chamber and said charge generating chamber at the time of explosion in another firing chamber.

5. In a carbide cannon, a plurality of symmetrically arranged firing chambers, means 115 for successively delivering explosive charges to each of said chambers, means for subsequently permitting the firing of said charge and means for scavenging each chamber after firing thereof.

6. In a carbide cannon, three symmetrically arranged firing chambers, a chamber common to the muzzle end of each of said chambers and through which each firing chamber discharges, a port associated with each of said chambers, a stationary sleeve normally closing said ports, a gas generating chamber and ports located in said sleeve for cooperation with said chamber ports for simultaneously permitting communication between said gas generating chamber and one of said firing 120 125 130

chambers and between each of said other chambers and the atmosphere and means for successively providing communication between said gas chamber and each of said firing chambers.

7. In a carbide cannon, a plurality of firing chambers, a chamber common to the muzzle end of each of said firing chambers and through which each firing chamber dis-
10 charges, a charge generating chamber, means for establishing communication between one firing chamber and said charge generating chamber at the time of explosion in another chamber and means for opening a third firing
15 chamber to the atmosphere at the time of said explosion.

8. In a carbide cannon, a plurality of firing chambers, a breech cylinder in which said chambers are formed and means whereby the
20 explosion in one chamber results in scavenging a second chamber and charging a third chamber.

9. In a toy cannon, a firing chamber, a subjacent water container, a magazine located
25 above said water container and means for delivering a gas forming material to said water container from said magazine and means for conveying the gas generated from said container to said firing chamber.

30 10. In a toy cannon, a firing chamber, a water container, a magazine located above said container, a sliding surface between said container and magazine provided with an opening for establishing communication
35 therebetween and means for moving said surface so as to deliver a charge of material to the container from said magazine.

11. In a toy cannon, a firing chamber formed in a rotatable breech cylinder having
40 an opening therein, a sleeve surrounding said cylinder so as to normally close said opening, a gas generating chamber having a conduit extending through said sleeve, means for rotating said cylinder so as to move the opening
45 therein into and out of communication with said conduit and means operated by rotation of said cylinder for delivering charges of gas forming material to said gas generating chamber.

50 12. In a toy cannon, a firing chamber formed in a rotatable breech cylinder having an opening therein, a sleeve surrounding said cylinder so as to normally close said opening, a gas generating chamber, a conduit associated therewith and communicating with the interior of said sleeve, means for rotating said cylinder so as to move the opening therein into and out of communication with said conduit, a magazine in said cylinder for gas
55 forming material, a partition separating said magazine from said firing chamber, charge delivering openings associated with said magazine and formed in the wall of said cylinder and means for rotating said cylinder
60 so as to move the opening of said firing chamber into and out of communication with said conduit and for moving said charge delivering openings into and out of operative position.

In testimony whereof, I have hereunto sub-
70 scribed my name this 13th day of February,
1929.
